UNITED STATES PATENT OFFICE.

HERBERT W. SCHWARTZ, OF CHICAGO, ILLINOIS.

HEADLIGHT DEVICE.

Application filed August 5, 1921. Serial No. 490,025.

To all whom it may concern:

Be it known that I, HERBERT W. SCHWARTZ, a citizen of the United States, residing at Chicago, in the county of Cook and State of Illinois, have invented certain new and useful Improvements in Headlight Devices, of which the following is a description.

My invention relates to improvements in head light devices and more particularly to a means for preventing glare due to the rays of light being projected upwardly of the reflector. With my improved device only the rays of light parallel to the principal axis and those reflected downwardly relative thereto are projected along the roadway, the others being absorbed or cut off. The invention has among its further objects the production of a device of the kind described which is simple, convenient, durable, reliable, efficient, and satisfactory for use wherever found applicable. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Figure 1 is a sectional view through my improved device;

Figure 2 is a front view thereof with the lens and holder removed; and

Figure 3 is a sectional view of a modified construction.

In the drawings, wherein I have illustrated two embodiments of my invention in one type, 1 indicates the outer casing or shell of a head light, said shell being adapted to detachably receive a lens holder 2 carrying a lens 3. The shell, lens and holder may be of any suitable size, shape or design, the specific construction as such not forming a part of my invention. Interiorly of the shell 1 is a mirror or reflector 4, said reflector being generally in the form of a concave spherical or parabolic mirror or polished surface. In the particular type shown there is positioned a bushing 5 of insulating material or the like, bored to re-

ceive an electrical conductor 6, extending through the casing 1 at 7, whereby it may be detachably connected to a suitable cooperating electrical conductor leading from any suitable source of energy, such as a generator, storage battery, or the like.

Ordinarily the light rays from a lamp positioned within the reflector at the focus or near it, will be reflected so that a glare will be produced, due to the upwardly directed rays which "fluids" and is dangerous to persons coming in the opposite direction or toward the light. With my improved device I provide means for restricting the direction of the reflected rays so that substantially none of them are reflected upwardly and hence a glare is not produced. An opaque cover or shield 8 having an annular flange 9 adapted to bear against the annular flange of the reflector 4 is positioned within the reflector, the lower half thereof being substantially of a contour parallel to the concave surface of the reflector so as to closely fit within and rest thereupon, the upper edges of the lower portion being indicated at 12 and being substantially straight and in a plane cutting the principal axis 27 of the reflector. In the wall of the shield at its bottom may be formed a conduit or channel 11 communicating at one end with the bushing 5 and at its other end with an aperture 13 formed in the wall of the cover so that the electrical conductor 6 may be inserted through said bushing and conduit and through said aperture inwardly of the headlight. The upper half of the shield is bent inwardly a slight distance, as at 14, so as to bear against a portion of the concave surface of the reflector, and thence bent outwardly and downwardly, as at 15, to overhang the reflector and form a visor, the lower edge of the visor is preferably arcuately recessed or cut, as at 16, from side to side and tends to prevent side glare. Secured to the lower portion 10 of the shield is a sleeve 18, arranged to adjustably or slidably receive a hollow bent arm 19-20, said arm being adjustably positioned therein and held in place by a set screw 22, or the equivalent. Into the arm 20 is positioned an adjustable or slidable sleeve 21, said sleeve being adjustably held in place by a set screw 23, or the like. The sleeve 21 is adapted to receive a lamp 24, so that the filament 25 of the same is substantially 105 110

2

arranged at the principal axis of the reflector. Thus the lamps may be adjusted as desired and held in any adjusted position. The entire lower portion 8 of the shield is 5 blackened or otherwise suitably treated to have a non-reflecting or a light absorptive surface, so that any rays of light thrown thereon will not be reflected from the surface thereof, but will be absorbed. The visor 15 10 may or may not be blackened to provide a non-reflecting surface just as desired, for as said visor 15 is made of an opaque material it will cut off all rays of light thrown against its inner surface so that all of the 15 rays of light directed onto the uncovered polished surface of the reflector 4 will be reflected therefrom along lines parallel to the principal axis of the mirror and also along lines lying in vertical planes and directed downwardly of the principal axis, the upper boundary of the rays reflected from the mirror being in the form of a curve corresponding to the arcuate recessed edge 16 of the visor 15. I prefer to opaque the 20 lamp as indicated at 24', so as to prevent the direct rays from being projected outwardly. This opaque may be foil, enamel, or the equivalent, which will reflect any rays onto the mirror or reflector proper.

30 Any other suitable manner of shielding the mirror so as to make it light absorptive may be provided, as for instance, a standard reflector might be employed and the polished surface of the lower half of the 35 mirror be painted over or darkened with any suitable material. With the last mentioned method, the shield 8 would comprise only the upper half or visor portion of the light-controlling means. The apparatus de- 40 scribed may be fitted into any type of lamp, or when the reflector is constructed as just mentioned it may replace the standard equipment. When a reflector is so constructed it may have the light terminal wire 45 brought in at the base of the part 18 and the offset part 11 omitted. Referring to Figure 3 this illustrates the construction referred to in which the reflector 30 is pro- 50 vided with a visor 31, and non-reflecting surface 32. In this case the wire 33 to the lamp 34 passes through an opening at the base of part 35. The lamp is preferably opaqued similar to lamp 24 in Figure 1.

The result is the same as with the other construction.

55

Having thus described my invention, it is obvious that various immaterial modifications may be made in the same without departing from the spirit of my invention; hence I do not wish to be understood as 60 limiting myself to the exact form, arrangement, construction, and combination of parts herein shown and described, or uses mentioned.

65

What I claim as new and desire to secure by Letters Patent is:

1. In a head light of the kind described and in combination, a concave reflector, a lamp adjustably positioned therein, means for covering the lower half of said reflector 70 to absorb the rays directed thereon, visor means transversely of said reflector at its upper half from a line within said reflector and extending outwardly and downwardly therefrom, said visor having an arcuate re- 75 cess in the lower free edge thereof whereby there will be no upwardly directed rays projected beyond the reflector and the light directed outwardly of said reflector will be bounded at its top edge by a down turned 80 arc corresponding to the arcuate recess in the transversely extending visor.

2. In a head light of the kind described and in combination, a concave reflector, a lamp arranged therein, means for absorbing the rays of light directed onto the lower half of said reflector, and a visor arranged transversely of said reflector at its upper portion from a point within said reflector and extending outwardly and downwardly 85 therefrom, said visor having a recess in the lower free edge thereof whereby there will be no upwardly directed rays of light projected beyond the reflector and the light directed outwardly of the reflector will be 90 bounded at its top edge by a line correspond- 95 ing to the lower bounding edge of the transversely extending visor.

In testimony whereof, I have hereunto signed my name in the presence of two sub- 100 scribing witnesses.

HERBERT W. SCHWARTZ.
